UNITED STATES PATENT OFFICE.

WILLIAM S. APPLEGATE, OF MAYS LANDING, NEW JERSEY.

ATTACHMENT FOR DOBBY LOOMS.

Application filed March 31, 1923. Serial No. 629,041.

To all whom it may concern:

Be it known that I, WILLIAM S. APPLEGATE, a citizen of the United States, and residing at Mays Landing, county of Atlantic, State of New Jersey, have invented certain new and useful Improvements in Attachments for Dobby Looms, of which the following is a specification.

The present invention relates to improvements in textile weaving looms and particularly to dobby looms.

The principal objects of the invention are to permit the weaving of more extensive and elaborate designs, or warp effects, with a dobby mechanism and to reduce the number of heavy working parts with a resulting reduction in the amount of power required to operate the loom. With the construction hereinafter described it is possible to obtain designs which heretofore have required a Jacquard loom or the use of a great many heddle frames in a dobby loom. The present invention permits the weaving of a greater number of warp effects without the use of a corresponding increase of heddle frames or the complicated mechanism of a Jacquard loom. The width and length of designs in textile fabrics woven on dobby looms in the past have been limited by the number of levers and heddle frames employed. Most dobby looms have between twenty and thirty top levers and the intricacy of the design is governed by the number of heddles which can be operated from these levers. In some designs it is necessary to raise or lower but a very few warp threads at certain stages of the weave. Where heddle frames are used the whole weight of the frame must be lifted. With the arrangement shown and described herein the weight of the mechanism for elevating the warp threads is considerably reduced and the number of levers for weaving designs has been greatly increased. This permits the weaving of designs with a greater variation in the control of the warp threads but with a saving in the power necessary to operate the loom.

These and other features of the invention, including certain details of construction and combination of parts are illustrated in the accompanying drawings forming a part of this specification. In the drawings:

Figure 1 is an elevation of a dobby loom constructed in accordance with this invention;

Figure 2 is an elevation of the arrangement for actuating the rocker-levers of the dobby heads;

Figure 3 and Figure 3^a are diagrams showing the relative sizes of figures woven on the looms now in use and a loom constructed in accordance with this invention.

In the form of the invention illustrated in the drawings dobby heads 10, 10' are shown positioned at each side of the loom frame 11. Top-levers 12, 12' are controlled by the pattern-chains 13, 13'. The rocker-levers 14, 14' are connected by means of the connecting-rod 15, so that the movements of rocker-lever 14 transmit corresponding movements to the rocker-lever 14'. The connecting rod 15 is provided at its ends with threaded couplings 16, 16', to allow for adjustment of the connection between the rocker-levers. The rocker-levers 14, 14' are fixed on rocker-shafts 17, 17' and are provided with arms 18, 18', but it is necessary to connect only one of these arms with the usual dobby driving mechanism. As shown in Figure 2, the arm 18 is connected through the lift-rod 19 with the cam-shaft 20. A gear 21 on the cam-shaft meshes with a gear 22 on the crank-shaft 23. Secured to the crank-shaft 23 is a pulley 24 through which power is transmitted to the crank-shaft from a belt 25. An idle pulley 26, onto which the belt may be shifted, is also mounted on the crank-shaft 23.

Each of the dobby-heads 10, 10' may be provided with any number of top levers, depending on the intricacy of design, the dobby heads in general use having from twenty to twenty-eight levers. Assuming for the purposes of description that there are twenty-six levers on each dobby head, at least four of these levers are attached to heddle frames 27 which are utilized to weave a base for the fabric. If desired, more heddle frames can be used to improve the ground weave. If, however, but four heddle-frames are used there then remain forty-eight levers which are available for the purpose of weaving designs in the cloth. To each of these levers is attached a design or neck cord 28 which passes over a sheave 29 and through a fixed distributor or comber-board 30. This comber board is perforated at regular intervals and extends across the width of the loom frame 11. Thus the design-cords may be spaced and separated in the same manner that harness-

- 2
- cords are spaced in the comber board used on the ordinary Jacquard loom. Additional neck-cords 31 may be attached to the cords 28 and passed through the comber-board.
- 5 In this manner the design may be repeated across the width of the weave, one additional neck-cord being attached to a design cord for each repetition of the design. Weights or lingoos 32, fastened to the ends 10 of the neck-cords, hold the cords taut and allow them to fall after being lifted by the top-levers 12, 12'. The warp threads pass through eyes 33 in the cords and heddle-frames.
- 15 The above dobby mechanism is of the ordinary construction except that there are two dobby-heads arranged at opposite sides of the loom, and only a sufficient number of heddle-frames for weaving the ground fabric 20 are attached to top-levers. In lieu of a heddle-frame for each lever, neck-cords, such as are used on Jacquard looms, are attached to the remaining levers. The additional dobby-head mechanism is actuated from the 25 rocker-lever of the dobby-head at the left side of the loom through the connecting-rod 15, thus making it unnecessary to provide means on the right end of the cam-shaft for actuating an additional lift-rod. Also, by 30 connecting the dobby-heads in this manner, the movements of the rocker-levers and the top-levers are synchronized and with the proper actuating means, as, for instance a pawl 34 and ratchet 35, the movements of 35 the pattern-chains are also synchronized. With this arrangement the entire mechanism can be operated in unison with the one lift-rod 19, as shown in Figure 2.
- The purpose of providing two dobby-40 heads at opposite sides of the loom is to allow the use of a large number of levers and a corresponding increase in the number of variations by which warp threads can be woven into a design. Instead of placing a 45 large number of top levers along one side of the loom, so that the dobby-head becomes unnecessarily long, it is possible with this arrangement, to employ a large number of levers for weaving wider and longer, as 50 well as more elaborate, designs on a dobby loom without increasing to any great extent the space taken up by the loom.
- As pointed out above, all of the levers, except those attached to the heddle-frames, 55 lift or lower the neck-cords through which pass the warp threads used in weaving the design in the fabric. The heddle-frames 27, four or more in number, lift and lower the ground warp threads. The remaining levers 60 are controlled by the pattern-chains 13, 13'.
- The pins in the pattern-chains are arranged to operate the levers in the proper sequence to lift or lower the design cords so that a predetermined design can be woven into the 65 fabric. With the large number of levers available for weaving designs it is apparent that very elaborate and complicated designs, such as woven in Jacquard looms, can be obtained. Also it is possible to greatly increase the width or length of a figure design. This is of great advantage in weaving articles such as towels, etc., in which it is desired to weave a large figure or name. It has been found by actual experience that the widths of the stripe and figure in towels, for 70 instance, have been increased from 2 to 3 times with a loom patterned after the above described construction. This is illustrated in Figures 3 and 3^a which show patterns made from a loom in which twenty-eight levers 80 are used and one having fifty-two levers.
- The operation of the loom will be apparent from the foregoing description. The dobby-heads 10, 10' are actuated by means of the crank-shaft 23, gears 21, 22, cam-shaft 85 20, lift-rod 19, arm 18, and the connecting rod 15. The heddle-frames for weaving the ground fabric are connected to four or more top-levers which lower and lift the heddle-frames continuously. The neck-cords, or design-cords, are attached to the remaining top-levers which are controlled by the pattern-chains 13, 13'. Each of the neck-cords passes over a sheave 29 and through a perforation in the comber-board 90 30. The pins in the pattern-chains control the sequence in which the levers are raised or depressed. The pins are so arranged that certain neck-cords will be lifted or lowered at the proper time so that a predetermined 95 pattern can be woven into the fabric. In the drawings one set of neck-cords for weaving one pattern is shown, but this pattern can be repeated several times across the width of the fabric by attaching additional 100 design-cords to the neck-cords which are fastened to the top-levers. Thus a series of design-cords, properly spaced along the comber-board, can be lifted or lowered together by one top-lever. In this manner 105 designs can be woven adjacent each other and with the large number of levers employed they can be made much wider and longer than those now woven on dobby-looms.
- 110 The advantages of the arrangement described above are evident. The weaving of designs heretofore requiring a Jacquard loom, with its complicated card and griff mechanism, may be done on an ordinary 115 dobby-loom. At the same time power is economized by eliminating many of the drawbacks incident to the employment of a large number of heddle-frames which, at best, are heavy and noisy. The additional 120 dobby-head would be a duplicate of the one already installed on the machine, both dobby-heads being of the usual types found on looms of this kind. This extra dobby-head can be attached to the loom with little 125 130

or no trouble, the only additional part being the connecting-rod which can be made from a wood or iron bar.

While the invention has been shown and described in detail it will be apparent that many changes may be made therein without departing from the spirit of the invention.

Having thus described the invention what is claimed as new and desired to be secured 10 by Letters Patent is:

1. In a loom for weaving figured fabrics, harness frames for raising and lowering ground warp threads, top levers for raising and lowering said harness frames, each harness frame being raised and lowered by a single top lever, neck cords for raising and lowering figuring warp threads, and a plurality of dobby mechanisms for selectively controlling said harness frames and 20 said neck cords.

2. In a loom for weaving figured fabrics, harness frames for raising and lowering ground warp threads, top levers for raising and lowering said harness frames, each harness frame being raised and lowered by a single top lever, neck cords for raising and lowering figuring warp threads, and dobby mechanism for selectively controlling said harness frames and said neck cords, part of 30 said dobby mechanism being located on one end of the loom and part on the opposite end of the loom.

3. In a loom for weaving figured fabrics, harness frames for raising and lowering ground warp threads, top levers for raising and lowering said harness frames, each harness frame being raised and lowered by a single top lever, neck cords for raising and lowering figuring warp threads, and dobby mechanism for selectively controlling said harness frames and said neck cords, half of 40 said dobby mechanism being located on one end of the loom and half on the opposite end of the loom.

4. In a loom for weaving figured fabrics, harness frames for raising and lowering ground warp threads, neck cords for raising and lowering figuring warp threads, top levers located on each end of the loom for 50 operating said harness frames and said neck cords, some of said neck cords being attached to top levers on one end of the loom and some to top levers on the opposite end of the loom, and dobby motion for selectively controlling said harness frames and said neck cords, part of said dobby motion being located on one end of the loom and part on the opposite end of the loom.

5. In a loom for weaving figured fabrics, harness frames for raising and lowering ground warp threads, neck cords for raising and lowering figuring warp threads, top levers located on each end of the loom for 60 operating said harness frames and said neck cords, some of said neck cords being attached

to top levers on one end of the loom and some to top levers on the opposite end of the loom, and dobby motion for selectively controlling said harness frames and said neck cords, half of said dobby motion being located on one end of the loom and half on the opposite end of the loom. 70

6. In a loom for weaving figured fabrics, harness frames for raising and lowering ground warp threads, neck cords for raising and lowering figuring warp threads, top levers located on each end of the loom for 75 operating said harness frames and said neck cords, some of said neck cords being attached to top levers on one end of the loom and some to top levers on the opposite end of the loom, a plurality of dobby mechanisms for selectively controlling said harness frames and said neck cords, and means connecting the dobby mechanisms for operating said 80 dobby mechanisms in synchronism.

7. In a loom for weaving figured fabrics, harness frames for raising and lowering ground warp threads, top levers for raising and lowering said harness frames, each harness frame being raised and lowered by a single top lever, neck cords for raising and lowering figuring warp threads, and a dobby mechanism comprising a plurality of head motions operating in synchronism for selectively controlling said harness frames and 90 said neck cords.

8. In a loom for weaving figured fabrics, harness frames for raising and lowering ground warp threads, top levers for raising and lowering said harness frames, each harness frame being raised and lowered by a single top lever, neck cords for raising and lowering figuring warp threads, and a dobby mechanism comprising a plurality of head 100 motions operating in synchronism for selectively controlling said harness frames and said neck cords, part of said dobby mechanism being located on one end of the loom and part thereof on the opposite end of the 110 loom.

9. In a loom for weaving figured fabrics, harness frames for raising and lowering ground warp threads, neck cords for raising and lowering figuring warp threads, top levers located on each end of the loom for 115 operating said harness frames and said neck cords, some of said neck cords being attached to top levers on one end of the loom and some to top levers on the opposite end of the loom, dobby mechanism including harness levers for operating harnesses and figuring levers for operating the neck cords, part of 120 said harness and figuring levers being located on one end of the loom, and part thereof on the opposite end of the loom, and pattern mechanism for controlling the dobby mechanism.

10. In a loom for weaving figured fabrics, harness frames for raising and lowering 125

- ground warp threads, neck cords for raising and lowering figuring warp threads, dobby mechanism including harness levers for operating harnesses and figuring levers for operating the neck cords, half of said harness and figuring levers being located on one end of the loom, and half thereof on the opposite end of the loom, and pattern mechanism for controlling the dobby mechanism.
11. In a loom for weaving figured fabrics, harness frames for raising and lowering ground warp threads, neck cords for raising and lowering figuring warp threads, dobby mechanism including harness levers for operating harnesses and figuring levers for operating the neck cords, part of said harness and figuring levers being located on one end of the loom, and part thereof on the opposite end of the loom, pattern mechanism for controlling each dobby mechanism, and means connecting the dobby mechanism for operating said dobby mechanisms and pattern chains in synchronism.
12. In a loom for weaving figured fabrics, harness frames for raising and lowering ground warp threads, neck cords for raising and lowering figuring warp threads, dobby mechanism including top levers at each side of the loom, means connecting one dobby mechanism with the opposite dobby mechanism for operating said dobby mechanisms in synchronism, and pattern mechanism associated with each dobby mechanism for selectively controlling the harness frames and neck cords, whereby the neck cords attached to the top levers on one side of the loom may be controlled independently of the neck cords attached to the top levers on the opposite side of loom.
13. In a loom, in combination, a dobby at each side of the loom, a rocker lever and top levers on each dobby, means connecting the rocker lever of one dobby with the rocker lever of the opposite dobby for oscillating
- said rocker levers in synchronism, harness frames for raising and lowering warp threads, each harness frame being raised and lowered by a single top lever, primary neck cords attached to others of said top levers, a series of secondary neck cords attached to each primary neck cord for lifting figuring warp threads, a comber board through which pass the secondary neck cords, pattern mechanism associated with each dobby for selectively controlling top levers, whereby the neck cords attached to the top levers on one side of the loom may be controlled independently of the neck cord attached to the top levers on the opposite side of the loom.
14. In a loom, in combination, a dobby at each side of the loom, a rocker lever and top levers on each dobby, an adjustable rod connecting the upper arm of one rocker lever with the lower arm of the opposite rocker lever to operate said rocker levers in synchronism, harness frames for raising and lowering warp threads, each harness frame being raised and lowered by a single top lever, primary neck cords attached to others of said top levers, a series of secondary neck cords attached to each primary neck cord for lifting figuring warp threads, a fixed comber board through which pass the secondary neck cords, a pattern chain connected with one rocker lever for controlling the top levers on one side of the loom, a second pattern chain connected with the opposite rocker lever for controlling top levers on that side of the loom, said pattern chains also moving in synchronism but provided with separate patterns, whereby the neck cords attached to the top levers on one side of the loom may be controlled independently of the neck cords attached to the top levers on the opposite side of the loom.

In testimony whereof I hereunto affix my signature.

WILLIAM S. APPLEGATE.
